(57) **CLAIM**

I claim the ornamental design for an A-frame grill cart, as shown and described.

DESCRIPTION

FIG. 1 is a perspective view of an A-frame grill cart according to the present invention;

FIG. 2 is a perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is a bottom view thereof.

The shelves and wheels in FIG. 2 are reduced to broken lines for ease of illustrating the rest of the frame, the claim being directed to the entire frame shown in FIGS. 1, 3-8. The kettle shown in broken lines in the drawings forms no part of the claimed design.
